United States Patent Office

Des. 213,528

Patented Mar. 11, 1969

213,528

AIRCRAFT

Lawrence B. Rellis, 734 NW. 80th St., Apt. 16,
Miami, Fla. 33150

Filed Sept. 13, 1967, Ser. No. 8,586

Term of patent 14 years

U.S. Cl. D71—1
Int. Cl. D12—07

Fig. 3

FIG. 6

FIG. 7

FIG. 1 is a perspective view of the aircraft, showing my new design;

FIG. 2 is a top plan view thereof;

FIG. 3 is a bottom plan view, with the front stabilizers in retracted position, thereof;

FIG. 4 is a side elevational view, thereof;

FIG. 5 is a view of the opposite side, thereof;

FIG. 6 is a front elevational view in the landing position, and

FIG. 7 is a rear elevational view of the aircraft.

I claim:

The ornamental design for an aircraft, as shown.
